INVENTOR:

H. M. Ryder,
BY A. R. Venaille

His ATTORNEY

UNITED STATES PATENT OFFICE.

HARRY M. RYDER, OF FOREST HILLS, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed May 15, 1924. Serial No. 713,550.

To all whom it may concern:

Be it known that I, HARRY M. RYDER, a citizen of the United States, residing at Forest Hills Borough, in the county of Allegheny and State of Pennsylvania, have invented certain new and useful Improvements in Railway-Traffic-Controlling Apparatus, of which the following is a specification.

10 My invention relates to railway traffic controlling apparatus, and particularly to apparatus of the type wherein the track rails are supplied with alternating current.

I will describe several forms of apparatus 15 embodying my invention, and will then point out the novel features thereof in claims.

In the accompanying drawing, Fig. 1 is a diagrammatic view showing one form 20 of apparatus embodying my invention. Figs. 2 and 3 are views showing modifications of the apparatus illustrated in Fig. 1 and also embodying my invention.

Similar reference characters refer to similar parts in each of the three views.

Referring first to Fig. 1, the reference characters 1 and 1^a designate the track rails of a railroad.

These rails are divided by means of insulated joints 2 into a plurality of successive blocks of which only one block A—C is shown in the drawing. This block is provided with a transformer T having a secondary 8 connected across the rails adjacent the left hand end of the block. The primary 9 of this transformer is constantly supplied with alternating current from a suitable source such as an alternator D. The current thus supplied to the trackway may 30 be used to control traffic governing apparatus of any suitable type such for example as train governing apparatus located on a train and receiving energy inductively from the track rails.

40 Under some conditions the length of block A—C may be such that the voltage at the right hand end due to the current from transformer T is undesirably low. To avoid this difficulty, I divide the block into two sections A—B and B—C by an insulated joint 2^a in at least one rail, and interpose an amplifier G between the two sections.

The amplifier G comprises a grid 3, a filament 4 and a plate 5. The filament 4 is supplied with current from a suitable source such as a battery 6. Grid 3 of tube G is connected with rail 1^a to the left of point B, and the filament 4 is connected with rail 1 adjacent point B. It is therefore plain that the electromotive force between rails at the right hand end of section A—B is applied between the grid and filament of tube G. The plate 5 of this tube is connected, through battery 7 and the primary 20 of a transformer Q, with the left hand side of filament 4, while secondary 21 of transformer Q is connected across the rails of section B—C.

It will be clear from the foregoing, that the electromotive force applied to the rails by transformer T is received from section A—B at point B, is amplified by tube G, and that a pulsating current of the same frequency and phase relation, but of greater amplitude, is supplied to the left hand end of section B—C.

In the modification shown in Fig. 2, the apparatus is similar to that shown in Fig. 1 with the single exception that a transformer K is interposed between the tube G and the track rails of section A—B. The primary 10 of this transformer is connected across the rails adjacent the right hand end of section A—B, and the terminals of secondary 11 of transformer K are connected with the grid 3 and filament 4 respectively of the tube G. The operation of the apparatus is the same as of the apparatus shown in Fig. 1, and will be understood without further explanation.

Referring now to Fig. 3, the plate circuit passes from plate 5, through a secondary winding 12 of a transformer M to the left hand end of filament 4. The primary 13 of this transformer is constantly supplied with alternating current of a lower frequency than that of alternator D from some suitable source such as an alternator F. Of course, current can flow in only one direction between filament 4 and plate 5 of tube G. During each alternate half cycle, then, currents flows through the plate circuit of tube G and into the rails of section B—C. During this half cycle however, the current supplied by transformer M is being varied,

or modulated, by the grid 3, the potential of which varies in accordance with the alternations in the electromotive force supplied by transformer T. A second secondary 24 on transformer M is connected across the rails of section B—C and receives energy from secondary 12. Section B—C is therefore supplied with energy in the form of surges of current each surge consisting of a plurality of impulses the phase and frequency of which are the same as the phase and frequency of the voltage in section A—B, but the amplitude of which is considerably greater than the amplitude of the voltage between rails at the right hand end of section A—B. For most practical purposes this intermittent supply is the full equivalent of a constant supply of the frequency of alternator D. To prevent current of the frequency of generator F from flowing into section B—C, a suitable filter 25 is interposed between the rails of the section and secondary 24.

Apparatus embodying my invention is particularly adapted for, though in no way limited to, the control of train carried governing apparatus arranged to receive energy inductively from the track rails. It should be particularly pointed out that with such apparatus the transformer action of the receiving means results in changing the pulsating current in the trackway in section B—C to an alternating current on the train.

Although I have herein shown and described only three forms of railway traffic controlling apparatus embodying my invention, it is understood that various changes and modifications may be made therein within the scope of the appended claims without departing from the spirit and scope of my invention.

Having thus described my invention, what I claim is:

1. In combination, a block of railway track comprising two sections, means for supplying an alternating voltage to the rails of one section, and means for amplifying said voltage and supplying such amplified voltage to the rails of the remaining said section.

2. In combination, a block of railway track comprising two sections, means for supplying an alternating voltage to the rails of one section, and an amplifier having its input circuit connected with the rails of said one section and its output circuit connected with the rails of the other section.

3. In combination, a block of railway track comprising two sections, means for supplying alternating current to the trackway in one such section, and an amplifying device receiving energy from said one section, and supplying energy to the trackway in the other said section.

4. In combination, a block of railway

track comprising two sections, a source of periodic voltage connected across the rails of one said section, an electron tube amplifier, means for supplying voltage from said one section to the grid circuit of said amplifier, and a plate circuit for said amplifier for supplying current to the rails of the remaining section.

5. In combination, a block of railway track comprising two sections, a source of periodic voltage connected across the rails of one said section, an electron tube amplifier, means for supplying voltage from said one section to the grid circuit of said amplifier, and a plate circuit for said amplifier including a source of direct current for supplying current to the rails of the remaining section.

6. In combination, a block of railway track comprising two sections, a source of periodic voltage of a first frequency connected with the rails of one section, an electron tube amplifier, means for applying voltage from said one section to the grid circuit of said amplifier, and a plate circuit for said amplifier for supplying current to the rails of the other said section and including a source of periodic current of a frequency different from said first frequency.

7. In combination, two successive sections of railway track, means for supplying a periodic voltage to the rails of one section, an electron tube amplifier, a transformer having a secondary winding included in the grid circuit of said amplifier and a primary winding connected with the rails of said one section, and a plate circuit for said amplifier for supplying current to the remaining section.

8. In combination, a block of railway track, means for supplying a periodic current to the trackway in one section, and means responsive to such current for supplying to the remaining section current having the same characteristics of phase and frequency as said first current but of greater amplitude.

9. In combination, a block of railway track, a source of alternating electromotive force connected across the rails adjacent one end of the block, an insulated joint in one rail at an intermediate point in the block, and means responsive to the voltage between rails on one side of said joint for applying across the rails on the other side of the joint an electromotive force having the same characteristics of phase and frequency as said voltage but of a greater amplitude.

10. In combination, a block of railway track, a source of alternating electromotive force connected across the rails adjacent one end of the block, an insulated joint in one rail at an intermediate point in the block, and an electron tube responsive to the voltage between rails on one side of said joint

for supplying a higher voltage across the rails on the other side of such joint.

11. In combination, a block of railway track, an insulated joint in one rail for dividing the block into two sections, a source of electromotive force connected across the rails of one of said sections remote from said joint, and an electron tube having a grid circuit receiving energy from the rails 10 of said section adjacent said joint and a plate circuit for delivering energy to the other section.

12. In combination, a block of railway track divided into two sections, a source of 15 alternating current for the first section, a second source of current for the second section, and an amplifier controlled by the alternating current in the first section for causing variations of the current supplied 20 to the second section by said second source

corresponding to the alternations in the first section but of greater amplitude.

13. In combination, a block of railway track divided into two sections, a source of alternating current for the first section, a 25 second source of current for the second section, and an amplifier for causing variations in the energy from said second source corresponding to the energy variations in the first section. 30

14. In combination, a block of railway track divided into two sections, a source of alternating current for the first section, a second source of current for the second section, and an amplifier for varying the current in the second section in accordance with the alternations of the current in the first section. 35

In testimony whereof I affix my signature.

HARRY M. RYDER.
